Patented Aug. 24, 1915.

UNITED STATES PATENT OFFICE.

GEOEGE P. VOSBRINK, OF CHICAGO, ILLINOIS.

DUST-MOP.

1,151,139.

Specification of Letters Patent. Patented Aug. 24, 1915.

Application filed July 30, 1914. Serial No. 854,079.

To all whom it may concern:

Be it known that I, GEORGE P. VOSBRINK, a citizen of the United States, residing at Chicago, in the county of Cook and State 5 of Illinois, have invented certain new and useful Improvements in Dust-Mops, of which the following is a specification.

This invention relates to improvements in mops, and particularly to mops of that kind 10 designed for cleaning and polishing floors and other surfaces, the primary object of the invention being to provide a mop in which the mop material is carried by a substantially triangular-shaped frame, whereby the 15 mop material, while disposed in compact shape, is arranged to cover a comparatively wide working area.

A further object of the invention is to provide a construction of triangular frame in 20 which the end portions of the metal of which the frame is made are turned inwardly at the base or wider end of the frame and disposed to serve as a means for connecting the mop handle with the frame, so that the 25 working pull or thrust will be transmitted in a direction parallel with the axis of the frame in manipulating the brush.

A still further object of the invention is to provide an adjustable handle and novel 30 means for mounting the same whereby the handle may be disposed for working action in a variety of positions and secured in any of its working positions against casual displacement.

35 The invention consists in the features of construction, combination and arrangement of parts hereinafter fully described and claimed, reference being had to the accompanying drawings, in which—

40 Figure 1 is a perspective view of a mop constructed in accordance with my invention; Fig. 2 is a similar view of the parts of the coupling connection between the handle and mop frame separated and arranged in proper relative positions; Fig. 3 is a detail view showing the terminals of the 45 mop frame; and Fig. 4 is a detail section through the pivotal connection between the frame and coupling head.

50 In carrying my invention into practice, I provide a mop comprising a substantially triangular- or heart-shaped frame 1 formed preferably of a strip of metal bent into the described shape. The vertex of this frame 55 portion faces forwardly, while the base or wider end of the frame is disposed at the

rear of the mop structure, at which end the frame strip 1 is bent inwardly. The ends are bent inwardly, as indicated at 2, and provided with forwardly-extending terminals 3. 60 These terminals 3 project into the space between the sides of the frame and are disposed in parallel relation and form a space or slot 4 at the rear of the frame to accommodate and permit of certain adjustments 65 of the mop handle 5, as hereinafter fully described. The frame 1 is inclosed in a cover or sheath 6 of fabric which serves as a base to which the mop material 7 is secured in any suitable manner, the fringe of mop material corresponding to the frame structure in contour, and being so arranged that the particles of the mop strands are mingled so as to form a broad working surface of substantially the full area of the brush structure, both longitudinally and transversely. 70 The cover or sheathing 6 may be of canvas, ducking or any other suitable strong and durable material whereby the mop material may be strongly and durably bound together 75 and supported upon the frame 1.

The handle 5 is provided at its lower end with a threaded stem 8 to adjustably engage the internally-threaded socket member 9 of a T-shaped coupling head 10, the cross portion 11 of which forms a sleeve to receive a bushing tube 12. The said sleeve 11 and tube 12 are disposed in alignment with openings 13 and 14 in the terminals 3 of the frame 1, one of which openings is of angular or non-circular form. A bolt 15 passes through the said openings 13 and 14 in the terminals 3 and also through the bushing 12 and pivotally connects the coupling head 10 with the frame 1, whereby the handle 5 may be adjusted to lie at any desired working angle between the vertical and horizontal. One end of the bolt is formed with the usual head 16 and an angular projection 17, while the other end of the bolt is threaded, as at 100 18, to receive a nut 19, which nut is arranged to bear against the terminal 3 having the circular opening 14, whereby the bolt will be held against casual displacement. The headed end 16 of the bolt is arranged to bear 105 against the other terminal 3 and its angular portion 17 fits within the angular opening 13 therein and enters the angular end 20 of the bore of the bushing 12, by which the bolt and bushing will be held from rotation, 110 allowing the coupling head 11 to turn upon the bushing.

It will be evident from the construction described that by turning the handle 5 to partially unscrew the stem 8 from the socket 9 the same will be moved out of engagement 5 with the bushing 12, whereupon the handle may be adjusted to the desired position, and then by turning the handle so as to screw the stem 8 into the coupling head and bring it into impinging engagement with the bush- 10 ing the handle may be locked in adjusted position, as will be readily understood. The construction described not only allows of the convenient adjustment of the handle, and its retention in adjusted position, but 15 the arrangement of the terminals 3 permits the handle to be moved fully down into the space 4 and also provides for the direct transmission of the pulling or pushing force in a longitudinal line centrally through the 20 mop, allowing the mop to be easily and conveniently manipulated.

I claim as my invention:

1. A mop comprising a frame member 25 bent into the form of a loop and having integral end portions arranged in spaced relation at the rear of the frame and terminating in portions which project in parallel and spaced relation into the space bounded by the frame, a coupling element pivotally en-

gaging said portions, and a handle provided 30 with a coupling element adjustably engaging the first named coupling element whereby the handle is vertically adjustable upon the frame member and is adapted to be locked rigidly in adjusted position, the said 35 coupling members being of a relative size to permit of their movement down into the space between the forwardly projecting ends of the frame member whereby the handle may be turned down to a substantially horizontal position. 40

2. A mop including a frame having inwardly and forwardly turned ends, a bolt connecting said ends of the frame and non-rotatably engaged therewith, a non-rotatable bushing upon the bolt, a T-shaped coupling head having its cross portion pivotally engaging the bushing and its body internally threaded to form a socket, and a handle having a screw stem adjustably engaging said socket and, adapted to impinge against said bushing. 45

In testimony whereof I affix my signature in presence of two witnesses.

GEORGE P. VOSBRINK.

Witnesses:

JOSEPH J. MARCHANT,
C. M. TURNQUIST.
